UNITED STATES PATENT OFFICE

EDWARD C. SNOODY, OF WINSTON-SALEM, NORTH CAROLINA

BABY BLANKET

Application filed November 20, 1930. Serial No. 487,003.

This invention relates to baby blankets and has for its object the provision of a crib blanket which shall keep the baby securely covered; which cooperates with the mattress to resist displacement; which is adjustable in size to accommodate it to any desired number of undercoverings; which has a front flap normally forming closed seams at its sides with the rest of the blanket but capable of being quickly turned down to give access to the baby for changing purposes; which preferably provides for exposure of the under-side of the mattress for ventilating the same and which can be opened flat for laundering.

15 Other objects of the invention will appear as the following description of a preferred and practical embodiment thereof proceeds.

In the drawing in which the same characters of reference have been used throughout the several figures to denote identical parts:

Figure 1 is a perspective view of a blanket embodying the principles of the invention in closed position;

25 Figure 2 is a similar view showing the blanket with the flap turned down;

Figure 3 is an underneath plan view of the blanket; and

Figure 4 is a plan view of the blanket spread flat.

Referring now in detail to the several figures, the numeral 1 refers in general to the blanket which is adapted to encompass a mattress as is suggested in Figures 1 and 2, being formed with slits 2 and 3 at its sides, and preferably adjacent the sides of the mattress, said slits extending from one end of the blanket and terminating short of the other end. The slits define a middle flap 4, side wing portions 5 and 6 and a foot portion 7.

The slits are preferably furnished with quick operable closures such for instance as the slide type seam fastenings 8.

45 The side wing portions 5 and 6 and the foot portion 7 are preferably provided with lacing eyelets 9 through which a cord or suitable lacing 10 may be strung so that the side wing portions and foot portion can be drawn toward one another beneath the mattress.

It will be understood that when the mattress is in position on the crib, the weight of the mattress holds the blankets against displacement. The lacing is adjustable to provide any desired degree of fullness for the blanket for the purpose of accommodating any number of layers of under-covers.

55 It will be understood that when the slide type fastenings are in closed position as shown in Figure 1, the child is securely covered and the seams closed in such a manner as to be draftproof. Figure 2 shows that the slide type fasteners may be quickly opened to permit the flap 4 to be turned down, giving access to the baby. Since the slits 2 and 3 are formed adjacent the sides of the mattress, the latter holds the wing portions 5 and 6 securely in position, preventing the blanket from sagging at the sides when the slide type fastenings are closed or opened.

60 It will be observed in Figure 3 that the side wing portions and foot portion are preferably of such size as to terminate short of the middle portion of the mattress, leaving the latter exposed and thus giving opportunity for the ventilation of the mattress.

65 It will be noted from Figure 4 that the blanket may be folded out flat to facilitate laundering and particularly ironing of the same.

70 It is of course, understood that the slide type fastenings may be substituted by other equivalent quick operable seam closing means, and that the lacing by which the side and foot portions of the blanket are brought toward one another beneath the mattress is merely illustrative of any desirable equivalent that may be adopted in practice.

75 What I claim is:

1. Crib blanket having longitudinal slits 80 on both sides extending from one end and terminating short of the other end, defining a flap bounded by side wing portions and a foot portion; means carried by said wing portions and foot portion for drawing said 85 portions toward one another beneath a mattress, and slide type fasteners for closing said slits.

2. Crib blanket comprising a flat member 90 adapted to cooperate with a mattress, said 95

member having longitudinal slits on both sides spaced apart substantially the width of the mattress, extending from one end and terminating short of the other end, defining
5 a flap bounded by side wing portions, adapted to extend under the sides of the mattress and to be retained in position by said mattress, and a foot portion adapted to tuck under the foot of the mattress, means for
10 drawing the wing portions toward one another beneath said mattress, and slide type fasteners for closing said slits.

In testimony whereof I affix my signature.
EDWARD C. SNODDY.
